UNITED STATES PATENT OFFICE.

EDWARD CHESHIRE, OF MILWAUKEE, WISCONSIN, ASSIGNOR, BY MESNE ASSIGNMENTS, TO MIEHLE PRINTING PRESS & MANUFACTURING COMPANY, OF CHICAGO, ILLINOIS, A CORPORATION OF ILLINOIS.

PRINTING PRESS.

Application filed June 21, 1920. Serial No. 390,327.

To all whom it may concern:

Be it known that I, EDWARD CHESHIRE, a citizen of the United States, residing at Milwaukee, in the county of Milwaukee and 5 State of Wisconsin, have invented certain new and useful Improvements in Printing Presses, of which the following is a specification.

This invention relates to a printing press, 10 and more particularly to means for positioning and registering sheet material before it receives an impression.

One object of the invention is to provide a simple, suitable and readily adjustable side 15 guide which is particularly adapted to accurately register sheets of material being fed, and particularly automatically fed to a vertical cylinder job press, such as that disclosed in my copending application, Serial No. 20 329,976, filed October 11, 1919.

Another object is to accurately determine the position of the pile on the stock table as a result of the adjusted position of a side 25 register which registers the sheet with respect to the printing form.

Another object is to make it possible to register interchangeably on either side of the press, particularly in the type of press hereinabove referred to.

Another object is to provide a simple and efficient side register for printing presses adapted to meet the various requirements for successful commercial operation.

These and other objects are accomplished 35 by means of the arrangements disclosed on the accompanying sheets of drawings, in which—

Figure 1 is a fragmentary plan view of a printing press embodying the preferred 40 form of my invention;

Figure 2 is a fragmentary enlarged plan view, parts being in section, of the side register mechanism disclosed in Figure 1;

Figure 3 is a fragmentary side elevation of 45 a cylinder transfer table and side register means at the instant when the transfer table receives a sheet and when the cylinder is at the top of its vertical stroke, the parts being shown on an enlarged scale;

Figure 4 is a side elevation of the same on 50 a reduced scale, with the exception that the cylinder is at the lower end of its vertical stroke and the other parts in their corresponding positions at instant of register;

Figure 5 is a view of the graduated register bar;

Figure 6 is a fragmentary plan view of a modified form of side register means; and,

Figure 7 is a view of the graduated register bar used in connection therewith.

The various novel features of my invention will be apparent from the following description and drawings and will be particularly pointed out in the appended claims.

This invention is illustrated preferably in connection with the type of printing press shown in my copending application, Serial No. 329,976, filed October 11, 1919, said printing press, among other things, including a main frame 10 in which the printing 70 form is reciprocated in a vertical plane, as also is the cylinder, said printing form and cylinder moving in opposite senses for reasons mentioned in said copending application.

Extending from the main frame is an arm 11, to which is pivotally connected at 12 a stock table frame 13 carrying a stock table 14, on which the sheet material to be fed to the press is placed. It will be understood that the frame 15, in which the cylinder 16 is rotatably mounted, is reciprocated vertically, said frame 15 being actuated by any suitable mechanism, which may be connected thereto at the point 17. A transfer table 18 at opposite sides is secured to arms 85 19, which in turn are pivotally connected at 20 to the cylinder frame 15. Accordingly, as the cylinder frame moves upwardly and downwardly, so does the transfer table.

This particular invention has to do primarily with side registering the sheets of material which are to receive an impression, the accurate positioning of the stock on the table with reference to the side register means after the latter has been accurately 90 positioned, and the relation between the side register means, transfer table and the stock table.

With these points in view, it will be noted that secured to the cylinder frame 15 at opposite sides of the cylinder are supporting brackets 21, in each of which is mounted a pin 22. Upon each of said pins 22 is pivotally supported a carrier arm 23 normally pressed upwardly by an associated torsion spring 24, as shown in Figures 1 and 3, the spring 24 being connected to the arm 23 and pin 22. The tension of the spring in

each case may be regulated by inserting a screw driver in the screw head of the pin 22 and the pin held in adjusted position by a set screw 25. The side register includes a 5 graduated bar 26 adjustably mounted in a groove 27 (see Figures 3 and 4) in the carrier arm 23, and is clamped in adjusted position by an overlying plate 28 and screw 29 which passes through the plate and into the 10 arm 23. Preferably, and as shown in Figures 1 and 2, the bar 26 has an integrally formed arm 27' extending at right angles thereto and provided with a tapped opening 68 into which is threaded for rotation a cup-shaped member 69, which may be secured 15 in any adjusted position by a nut 30. Said cup-shaped member has an opening therethrough for the reception of a rotatably and longitudinally movable pin 31 having an 20 enlarged head 32 with an aperture therethrough for slidably receiving the side register bar 33. The cup member 69 has a diametrically extending slot 34 therein for accurately positioning the bar 33 with respect 25 to the level of the transfer table for maintaining the adjusted position, even though the bar is removed from the groove, in a manner to be referred to later. In this connection a spring 35 is coiled around the 30 outer end of the pin 31 and is interposed between one end of the member 69 and a washer 36 secured to one end of the pin 31, whereby the bar 33 is yieldably clamped or retained in the slot 34 of the member 69. 35 If, however, it is desired to rotate the register bar 33 from its normal functioning position, for example, when it is desired to remove the transfer table, the same may be accomplished by forcing the bar 33 laterally (using a screw driver fulcrumed in an 40 adjacent notch 70), compressing the spring 35 until the bar 33 is beyond the confines of the slot 34, whereupon the bar may be rotated the desired amount. However, the 45 position of the slot remains unaltered. When the bar 33 is rotated back to its original position, it will re-enter the slot 34 to occupy the position it had prior to its withdrawal, without any variations with respect 50 to its position relative to the upper surface of the transfer table. With the portion of the head 32 located in the cup portion of member 69 and the bar 33 in the slot 34 of member 69, the bar 33 is clamped securely by the action of the spring 35. One 55 end of the register bar 33 is provided with a tapped portion for the reception of an adjustable stop member 37 and terminates in a pin 38, said stop member 37 and its pin 60 38 during the action of registering passing into one of a plurality of grooves 39 in the transfer table. The stop member 37 is threaded into the bar 33 for making the final minor or delicate adjustment in connection 65 with registering the sheet material,

and is held in adjusted position by a pin 40 having a pointed end receivable in one of a plurality of notches in one side of the stop member 37, the pin being yieldably forced into such notches by a spring 41 secured to the bar by any suitable means 42.

In connection with the operation of the side register mechanism, after "make-ready" it becomes necessary to locate or side register the sheet with reference to the printing form. 75 In this connection a sheet of paper 43 is placed on the transfer table 18, usually by hand, in approximate location and the adjustable side guide or bar 33 with its attached parts is adjusted to stop the sheet 80 (when the cylinder is at the lower end of its travel) for a trial impression. Error in the location as revealed by the trial impression, may be corrected by the further adjustment of the side register, that is, by 85 moving the graduated bar 26, which is connected to the side bar 33, longitudinally in the groove 27 of the carrier arm 23, whereupon the graduated bar 26 and its associated parts will be again clamped in position by 90 the screw 29. It may be necessary to make a finer adjustment. This may be done by rotating the stop button 37 one way or the other, whereupon it will be held in adjusted position by the spring-pressed pin 40. It 95 will be understood that the bar 33 is adjustable with respect to the graduated bar 26, and also with respect to the transfer table 18, so that the stop button 37 and pin 38 may occupy any one of the grooves 39 in the transfer table 18, so that the stop button 37 will be approximately in the middle of the side edge of any sheet used. As soon as 100 the sheet is definitely located on the transfer table, the indication on the slidably adjustable graduated bar 26 will be observed, and this indicates and determines the location of the stock pile 44 on the stock table 14, as it is now only necessary to adjust the stock guide 45 and its attached block 46 to 105 the same reading on the scale 47 as indicated by the scale on the graduated bar 26. Accordingly, stock may then be placed against the guide 45 and the other three guides 48, 49 and 50 adjust to retain the stock pile 110 in contact with the pile guide 45. A sheet now taken from the stock pile by automatic means and deposited on the transfer table will be off side register by a predetermined amount, as indicated 115 at 51. The dipping motion of the transfer table from the position shown in Figure 3 to the position shown in Figure 4, it being understood that the transfer table is dipped by any suitable mechanism through a connection, as at 52, first registers the sheet against the cylinder grippers 71 and then a sidewise movement of the transfer table 120 (as described in my said copending application) carries the sheet against the side regis- 125 ter 130

ter button 37, which at this time has been lowered from its elevated position, as shown in Figure 3, to its functioning position, as shown in Figure 4, by a cam 52' cooperating with a member 53 secured to the carrier 23. As soon as the sheet has reached its limit of sidewise movement, it is seized by the cylinder grippers 71, and as it is withdrawn from the transfer table, the side register bar 33 moves upwardly out of engagement with the sheet, under the influence of the coiled spring 24, the upward movement of the side registering mechanism being limited by a projection 54 on the carrier member 23 passing into engagement with a stop 55 on the bracket 21. It is important that the side register bar be raised before the paper is drawn from the transfer table by the cylinder, because the side register stop button 37 would soon become marked and rendered inaccurate. The pin 38 serves the function of carrying the sheet down with it at the instant of side registering and insures perfect register by bringing the sheet into correct alignment at the required time, the pin being especially valuable in case that the sheet is bent or curly.

If desired to have the sheets register at the opposite side of the press, the same may be done by removing the graduated slide bar 26 and its attached parts, from the carrier arm 23 at the left-hand side and placed in position in the carrier arm 23 at the right-hand side of the machine, in which event the guide 48 on the stock table would be the pilot guide.

A modification of the side register mechanism is shown in Figures 6 and 7, in which the side register bar 56 has secured at its outer end a fixed stop button 57 and pin 58, the minor or fine adjustment being made by adjusting the pivotally mounted bar carrier 59 with respect to the graduated laterally slidable bar 60, through the actuation of a nut 61 threaded on a stud 62, around which is coiled a spring 63 located intermediate the bar 60 and an arm of the bar carrier 59. The side register bar 56 is adjustably held in position by means of a clamp 64 associated with the bar carrier 59, which is pivotally connected at 65 to the graduated slide bar 60. The other parts are the same as that shown in the main figures of the drawing which disclose the preferred form.

It is apparent that there may be various other modifications of the invention as herein particularly shown and described, and it is my intention to cover all such modifications which do not involve a departure from the spirit and scope of the following claims.

I claim:

1. In side register mechanism for printing presses having a main frame, a cylinder frame and a transfer table, and side register means carried by said cylinder frame and

in a relative movement cooperating with said transfer table for registering a sheet of material on said transfer table.

2. In side register mechanism for printing presses having a main frame, a cylinder frame and transfer table, said main and cylinder frames being relatively movable during the impression stroke, and side register means associated with said cylinder frame and in a relative movement cooperating with said transfer table when said frames are in a given relative position for registering a sheet of material on said transfer table.

3. In a printing press, the combination of a cylinder frame having a vertical movement during the impression stroke, and side register means carried by said frame.

4. In a printing press, the combination of a movable cylinder frame, an impression cylinder carried thereby, and side register means carried by said frame and being movable with respect thereto for side registering purposes.

5. In a printing press, the combination of a stock table, side register means for registering a sheet of material before it receives an impression, and means whereby stock may be accurately and definitely positioned on said stock table without a trial positioning after the position of the side register means is determined and in accordance therewith.

6. In a printing press the combination of a stock table, side register means for registering a sheet of material before it receives an impression, and graduated means associated with said register means and stock table whereby stock may be accurately and definitely positioned on said stock table after the position of the side register means is determined and in accordance therewith.

7. In a printing press, the combination of a stock table, side register means for registering a sheet of material before it receives an impression, and means associated with said register means and stock table whereby stock may be accurately and definitely positioned on said stock table without a trial positioning after the position of the side register means is determined and in accordance therewith.

8. In a printing press, the combination of a stock table, and side register means including a graduated member which serves to indicate the position which the stock pile is to take on the stock table.

9. In a printing press, the combination of a stock table having graduations, and side register means having graduations which serves to indicate the position which the stock pile is to take on the stock table, the stock being positioned on said stock table with respect to its graduations corresponding to the indication on the side register graduated means.

10. In a printing press, side register means including a slidably mounted graduated bar which serves to indicate the position which the stock pile is to take preparatory to being fed sheet by sheet to receive an impression. 65
11. In a printing press, graduated side register means which serves to indicate the position which the stock pile is to take preparatory to being fed sheet by sheet to receive an impression. 70
12. In a printing press, the combination of a transfer table, and normally bodily movable side register means adjustable in a sheet feeding direction with respect thereto for presenting a stop portion at the middle of sheets of varying width. 75
13. In a printing press, the combination of a transfer table having a plurality of grooves therein, and side register means including a stop member adapted to pass into any one of said grooves for use in connection with registering sheets of varying widths. 80
14. In a printing press, the combination of a transfer table, and normally bodily movable side register means adjustable in a plurality of directions with respect to said transfer table including the direction of sheet feeding for registering sheets prior to receiving an impression. 85
15. In side register mechanism for printing presses, the combination of a cylinder frame, a supporting member carried thereby and adjustable in a given direction for a general positioning of the side register means, and means associated therewith for making a fine adjustment. 90
16. In side register mechanism for printing presses, a member having a groove for determining the position of a side register bar, and a side register bar movable into and out of said groove without changing the adjustment in a given direction, and a sheet stopping member carried directly on said bar. 100
17. In side register mechanism for printing presses, a member having a groove for determining the position of a side register bar, a side register bar movable into and out of said groove without changing the adjustment in a given direction, and a stop member adjustably mounted in said bar. 105
18. In side register mechanism for printing presses, a support, and a side register member movable with respect to said support and normally occupying in a given sense a predetermined position with respect thereto for side registering purposes, and sheet stopping means carried directly on said member. 115
19. In side register mechanism for printing presses, a cylinder frame, means carried thereby for passing into engagement with a sheet at the instant of register to make the register perfect regardless of the condition of the sheet. 120
20. In side register mechanism, the combination of a cylinder frame, and means carried thereby for forcing a sheet of material downwardly and for limiting its sidewise movement preparatory to receiving an impression.
21. In side register mechanism for printing presses, the combination of a cylinder frame, and associated members carried thereby, one for passing into engagement with the top side of a sheet so that it will engage a side stop member and the other a side stop member for limiting the lateral movement of the sheet.
22. In a printing press, the combination of a transfer table, a cylinder frame, an impression cylinder carried thereby, and side register means carried by said impression cylinder frame adapted to cooperate with said transfer table at either side thereof.
23. In a printing press, the combination of a transfer table, a cylinder frame, an impression cylinder carried thereby, and interchangeable means supported by said frame adapted to be mounted at either side of said transfer table for side registering at each side.
24. In a printing press, the combination of transfer means, a cylinder frame, an impression cylinder carried thereby, and interchangeable means supported by said frame adapted to be mounted at either side of said transfer means for side registering at each side.
25. In a vertical type of printing press, the combination of a transfer table, a cylinder frame movable in a vertical plane during the impression stroke, side register means carried thereby and associated with said transfer table, and means for moving said side register means out of engagement with a sheet of material as the latter is being withdrawn from said transfer table to prevent wear of the side register means. 110
26. In a printing press, the combination of a cylinder having grippers, a movably mounted transfer table arranged adjacent said cylinder and movable with respect thereto for front registering, and side register means associated with said transfer table and movable out of engagement with a sheet of material as it is being drawn from the transfer table by the cylinder grippers to prevent wear of the side register. 115
- Signed at Milwaukee, Wisconsin, this 18th day of June, 1920.

EDWARD CHESHIRE,
